UNITED STATES PATENT OFFICE.

EDGAR M. SORENG, OF CHICAGO, ILLINOIS, ASSIGNOR TO BRIGGS & STRATTON COMPANY, OF MILWAUKEE, WISCONSIN, A CORPORATION OF WISCONSIN.

STOP-LIGHT SWITCH.

Application filed June 28, 1922. Serial No. 571,522.

To all whom it may concern:

Be it known that I, EDGAR M. SORENG, a citizen of the United States, and resident of Chicago, in the county of Cook and State of Illinois, have invented new and useful Improvements in Stop-Light Switches, of which the following is a description, reference being had to the accompanying drawings, which are a part of this specification.

10 This invention has for its object to provide a strong and durable switch mechanism for closing a lamp circuit incidental to the operation of the brake or clutch of an automobile and thereby cause a signal lamp to 15 burn indicating to those in the rear that the automobile is about to stop.

An object of the invention is to simplify the construction of switches for this purpose and to make them inexpensive to manufacture.

With the above and other objects in view the invention consists of the stop light switch as herein claimed and all equivalents.

Referring to the accompanying drawings 25 in which like characters of reference indicate the same parts in different views,

Fig. 1 is a front view of a stop light switch constructed in accordance with this invention;

30 Fig. 2 is a longitudinal sectional view thereof on the plane of line 2—2 of Fig. 1;

Fig. 3 is a back view;

Fig. 4 is a view with the back-plate removed and the stem withdrawn for closing 35 the switch;

Fig. 5 is a sectional view on the plane of line 5—5 of Fig. 2;

Fig. 6 is a sectional view on the plane of line 6—6 of Fig. 2, and

40 Fig. 7 is a detail view of the contact member.

In these drawings 10 indicates a casing preferably of sheet metal bent up to form a rectangular housing for the switch mechanism, which is mounted on a back-plate 11, by having lugs 12 at its ends entering slots 13 of the back-plate and by having ears 14 at its sides passing through notches 15 in the edge of the back-plate and bent over behind 50 the back-plate.

A plate 16 of fiber or other insulating material is riveted within the casing 10 at one end thereof and passing through this insulating plate and riveted thereto are reversely 55 bent contact arms 17, the outer ends of which

pass through openings in the casing, which, as shown in Fig. 1, are sufficiently large to leave a wide clearance around the said arms and their attaching rivets to avoid electrical connection between the casing and the contact 60 arms. The outer ends of the contact arms have screws threaded in them to form binding posts 18, while their inner ends stand out from the insulating plate 16 in position to have a contact member engage therewith. 65 The contact member is formed by a plate of insulating material 19 having a metal strap 20 riveted on its back by means of rivets 21 which extend through said insulating plate to engage the ends of the contact arms, as 70 seen in Fig. 4, and thus establish a bridging connection between them through said metal strap. The contact member is urged toward the contact arms by means of a pair of coiled springs 22 confined between the ends of said 75 contact member and the end of the casing, there being, however, a sheet of insulating material 23 on the back of the contact member to prevent the springs constituting an electrical connection between the metal strap 80 and the casing.

Both the side edges of the insulating plate 19 and the insulating sheet 23 are notched, as shown in Figs. 6 and 7, to avoid engagement with the rivet which holds insulating plate 85 16 in place. Both edges are notched so that it is immaterial which edge is next to the rivet. The end of the casing is intended to form an inwardly projecting boss 24 to hold the ends of the springs 22 properly spaced 90 apart.

The contact member is normally held off of the contact arms against the pressure of its springs 22 by means of a spring-actuated stem 25 preferably consisting of a strip of 95 sheet metal passing freely through a slot in the end of the casing and surrounded by a coiled spring 26 which bears at one end against the end of the casing and at the other end against a follower plate 27 fixed 100 on the stem. The follower plate is fixed on the stem by having a slot receiving the stem and by being pressed by the spring against shoulders of the stem formed by lugs 28 cut from the edge of the stem and bent out of the 105 plane thereof. The follower plate extends across the casing and loosely fits the walls thereof so as to constitute a guide for the stem but its movement is arrested by its engagement with the edge of the insulating 110

plate 16, as shown in Fig. 2, which forms a stop for that purpose. In this position of the stem its inner end bears against the contact member and holds it away from the contact arms, as seen in Fig. 2, the spring 26 being of sufficient strength to overcome the springs 22. When the stem is withdrawn, however, to compress the spring 26 and move the follower plate 27 away from its stop, the contact member returns under the pressure of its springs into engagement with the contact arms 17 to reestablish the electrical connection between them.

In use, the casing is secured to the body 15 of the automobile in any desired manner, as by means of screws passing through attaching ears 29 on the back-plate or the casing or both while a chain or cable connection is made between the stem 25 and the brake 20 treadle or other part, the movement of which is desired to establish the signal connection. With the terminals of the signal lamp circuit connected with the respective binding posts 18, the operation of the brake 25 treadle or other part serves to draw the stem 25 outwardly against the pressure of spring 26, thus permitting the contact member to establish connection between the contact arms and so close the signal circuit. The 30 return of the brake treadle permits the spring 26 to return the stem and dislodge the contact member to interrupt the signal circuit.

While the mechanical construction of the 35 switch mechanism of this invention is exceedingly simple and inexpensive, it is strong and durable and designed to give continual service without requiring attention and without the wear of parts. The 40 contact member guided between the walls of the casing and the insulating plate 16 and held by the pressure of the two springs, against the two contact arms, except when displaced by the pressure of the stem at its 45 center, requires no other mounting or support and is not liable to failure of contact.

What I claim as my invention and desire to secure by Letters Patent is:

1. In a switch, a casing, a contact member loosely contained within the casing and guided thereby, contacts within the casing in the path of the contact member, spring means bearing on the contact member for moving it into engagement with the contacts, and a retractile spring member engaging the contact member to hold it out of engagement with the contacts.

2. In a switch, a casing, contacts therein, a spring-actuated loosely mounted floating contact member for engaging said contacts and guided in its movements by the casing,

and a spring-actuated retractile displacing member for holding the contact member out of engagement with the contacts.

3. In a switch, a casing, an insulating plate secured therein, contact arms secured to the insulating plate with their inner ends forming contacts within the casing and their outer ends forming circuit connecting means projecting from the casing, a contact member loosely mounted in the casing, springs confined between the end of the casing and the contact member for moving the contact member into engagement with the contacts, and a spring-pressed retractile means engaging the contact member for forcing it out of engagement with the contacts.

4. In a switch, a casing, contacts therein, a contact member loosely mounted within the casing, springs bearing on the ends of the contact member for moving it into engagement with the contacts, a stem slidably mounted in the casing, a follower on the stem guided by the casing, and a spring surrounding the stem and bearing on the casing and on the follower, the end of said stem engaging the contact member for forcing it away from the contacts.

5. In a switch, a casing, contacts therein, a contact member loosely mounted within the casing for engaging the contacts near its ends, coiled springs bearing on the contact member near its ends to hold it in engagement with the contacts, and a spring-pressed stem guided in the casing and engaging the contact member near its center to force it out of engagement with the contacts.

6. In a switch, a casing, an insulating plate secured within the casing, contact arms riveted to the insulating plate and forming contacts within the casing, at their inner ends and circuit connecting means projecting from the casing at their outer ends, a contact member comprising a plate of insulating material having a metal strap riveted on its back by rivets adapted to engage the contacts, coiled springs confined between the contact member and the end of the casing, a stem slidably mounted in the end

of the casing, a follower plate on the stem engaging the contact carrying insulating plate as a stop, a coiled spring surrounding the stem and bearing on the end of the casing and on the follower plate, the end of the stem serving to engage the contact member and hold it away from the contacts, and a back-plate secured to the casing and forming a guide for the follower plate and for the contact member.

In testimony whereof I affix my signature,

EDGAR M. SORENG.
